UNITED STATES PATENT OFFICE

2,479,720

EXTENSION LAMP SUPPORT

Robert J. Brandt, Hollywood, Calif.

Application April 12, 1947, Serial No. 741,058

5 Claims. (Cl. 248—124)

1

The invention relates to an extension lamp support and more particularly to an extension support for one or more lamps of different sizes whereof the lamps may be of the character known as a baby junior, or junior, employed to illuminate sets or scenes to be photographed.

It is necessary to be able to adjust the position of the lamp with respect to the set or scene in order to obtain the desired lighting effect, and for this purpose it is old to use certain supports which have defects overcome by the present invention. According to one of the former supports, a counterweight is fixed on the base of the stand, in order to counterbalance a particular lamp on the stand. This has the disadvantage that if it is necessary to substitute one lamp for another it is necessary to move away a particular stand with its fixed lamp and counterweight, and substitute another one, thereby losing valuable time, bearing in mind the high production costs in motion picture studios. It should also be noted that the junior lamp referred to above weighs about three times as much as the baby junior, which makes it apparent why it is necessary to substitute one stand for another when using the type of stand having a fixed counterweight on its base. A similar disadvantage is present in another prior lamp support wherein the counterweight is fixed at the end of a tilt lamp arm held in adjusted tilted position by a quadrant. This particular lamp support also has the disadvantage that it is necessary to move the stand bodily when adjusting the distance from the lamp to the subject.

All of these defects are overcome according to the present invention which has for an object to provide an extension support for photographic lamps of the character described, and wherein the distance of the lamp from the subject may be adjusted without moving the stand and wherein the support may be readily counterbalanced for different extended positions of the lamp and also for lamps of different weights.

For further details of the invention, reference may be made to the drawings wherein Fig. 1 is a view in front elevation of an extension lamp support according to the present invention.

Fig. 2 is an enlarged vertical sectional view of the spindle of the lamp support and a socket therefor, with parts broken away.

Fig. 3 is an enlarged view in elevation, partly in vertical section of the counterweight and its support.

Fig. 4 is an enlarged view in elevation partly

2

in vertical section of the lamp extension arm and its support.

Referring in detail to the drawings, the extension lamp support 1 comprises a rigid triangular frame work or truss 2 having a base in the form of a horizontal tubular support or pipe 3 and sides in the form of an angular tie rod 4. The intermediate portion of tie rod 4 forms the apex of the triangle and is welded as indicated at 5 to a strut 6. Strut 6 is above the axle 44 and it arises from pipe 3 and is welded thereto at its lower end as indicated at 60. One end of rod 4 is welded as indicated at 7 in Fig. 3 to a fitting 8, and the other end of rod 4 is welded as indicated at 9 to a similar fitting 10. The support 3 is a pipe having one end 11 thereof which fits in a socket 12 in the fitting 8, and welded thereto as indicated at 13 and the other end 14 of the pipe 3 fits in a socket 15 in the fitting 10, and welded thereto as indicated at 16.

The fitting 8 has an internal shoulder 17 which serves as a stop for the enlarged end 18 of the counterweight arm 19 which slides in a bore 20 in the fitting 8. The arm 19 is held in its adjusted position by a screw clamp 21 mounted on the fitting 8. The counterweight 22 has a bore 23 to receive the arm 19, the weight 22 being slidable on arm 19 and held in adjusted position by a screw clamp 24 on the weight 22. To prevent the accidental removal of weight 22 when screw clamp 24 is loose, the outer end of arm 19 has a bolt 25 with a nut 26 which serves as a stop. The nut 26 can be removed when substituting one weight for another weight, to balance a lamp of a different weight. Also, the effectiveness of the weight 22 as a counterbalance can be adjusted either by adjusting the position of weight 22 on arm 19 or by adjusting the position of arm 19 in its fitting 8. The fitting 10 is similar to the fitting 8 and it slidably carries an extension arm 27 which is held in adjusted position by a screw clamp 28 mounted in the fitting 10. Also, the complete withdrawal of arm 27 is prevented by its upset end 29 abutting against an internal shoulder 30 in the fitting 10, as previously described in connection with fitting 8.

The arms 19 and 27 are assembled in working position shown by first inserting them in their respective fittings 8 and 10, and then welding the fittings 8 and 10 on the opposite ends of the pipe 3.

Extending in line with the arm 27 along the axis thereof is an axle 31. The axle 31 is welded to the arm 27 as indicated at 32 and a similar axle 33 extends vertically downward from the

arm 27. The axles 31 and 33 each receive the socket 34 on the yoke 35 of the lamp 36. Lamp 36 has a trunnion in its yoke and is clamped in its rotatable position by a pair of clamps indicated at 37, as well known. Also, the socket 34 is rotatable on its axle 31 and is clamped in adjusted position by a screw clamp 38. The axle 31 has an annular groove 39 to receive the inner end of the clamp 38 and the outer end of the axle 31 has a cross bore 40 for a cotter pin 41 or the like which serves as a stop to prevent the socket 34 from accidentally sliding off from the axle 31. A lamp, such as 36, can be mounted on one or both of the axles 31, 33.

One operator can vary the distance of the lamp 36 from the scene to be photographed by sliding or telescoping arm 27 in its socket 10, while another operator slides or telescopes the arm 19 in the socket 8 and if necessary, also slides the weight 22 on the arm 19, to counterbalance the weight of the lamp 36. If two lamps are used at the same time on the axles 31 and 33 or if a lamp of a different weight is substituted, a particular counterweight 22 can be readily removed from arm 19 by removing nut 26 and a heavier similar weight substituted therefor as required.

The truss 2 is supported for adjustment to various heights and for rotation about a vertical axis and for this purpose, pipe 3 has a depending spindle or axle 44 welded to a collar 45 as indicated at 46. Collar 45 fits in a hole 47 in pipe 3 and is welded thereto as indicated at 48. Collar 45 rotatably rests on the upper end of a fitting 49 having a screw clamp 50 to engage the reduced section 51 on the axle 44. The truss 2 can thus be rotated to different positions and clamped in its rotated position by the clamp 50. The fitting 49 has a depending pipe 52 which can be raised or lowered in fitting 53 which has a screw clamp 54 to hold the pipe 52 at its adjusted height. Fitting 53 has a pipe 55 which fits in a pipe 56 arising from the base 57 which has a suitable number of rollers 58. The pipes 52, 55, 56 telescope with each other and can be rotated as well as extended or retracted and held in adjusted position by clamps 54 and 59.

Instead of supporting the axle 44, as shown in Fig. 2, in the socket of a fitting 49, axle 44 may be supported on a stand which terminates in a vertical rod, and for this purpose axle 44, at its lower end, has a bore 61 to receive such rod, with a cross aperture 62 to receive a pin and lock it to the rod.

Various modifications may be made in the invention without departing from the spirit of the following claims.

I claim:

1. An extension lamp support comprising a

truss having a tubular horizontal support, a spindle fixed to an intermediate portion of said support, an extension arm telescopically mounted in each end of said support, a clamp at each end of said support for each of said arms, an axle on one of said arms for receiving the socket of a lamp support, the other of said arms having a counterweight to counterbalance the lamp, and an extensible vertical support terminating at its upper end in a socket for said spindle.

2. An extension lamp support according to claim 1 comprising a fitting secured to each end of said support, each of said fittings having a socket in which one end of said tubular support is fixed, each of said fittings having an internal shoulder serving as an abutment and a cooperating shoulder on the inner end of each of said arms to limit withdrawal of said arms from said support when its clamp is inactive, said truss having an angular tie-rod secured at its ends to said fittings.

3. An extension lamp support according to claim 1 comprising a counterweight having a bore for its said arm, a screw clamp in said counterweight to hold the same in adjusted position on said arm, and a removable stop at the end of last said mentioned arm limiting outward sliding movement of said counterweight.

4. An extension lamp support comprising a tubular horizontal support, a spindle fixed to and depending from an intermediate portion of said support, an extension arm telescopically mounted in each end of said support, a clamp at each end of said support for each of said arms, an axle on one of said arms for receiving the socket of a lamp support, the other of said arms having a counterweight to counterbalance the lamp, said counterweight arm being extensible to an adjustable position to counterbalance the adjusted extension of said lamp support arm.

5. An extension lamp support according to claim 1 wherein said truss comprises a strut fixed to said tubular support opposite said spindle.

ROBERT J. BRANDT.
